(57) **CLAIM**

The ornamental design for an end bracket for forkable base stand, as shown and described.

DESCRIPTION

FIG. 1 is a left side plan view of an end bracket for a forkable base stand;

FIG. 2 is a front plan view of the end bracket;

FIG. 3 is a rear plan view thereof;

FIG. 4 is a right side plan view thereof;

FIG. 5 is the top end view thereof;

FIG. 6 is a bottom end view thereof; and,

FIG. 7 is a perspective view thereof.

The broken lines showing of partial structure and openings are included for the purpose of illustrating environment and forms no part of the claimed design.
